Patented Oct. 12, 1920.

UNITED STATES PATENT OFFICE.

ANGELO M. TOZZI, OF BAYONNE, NEW JERSEY.

LEAD OR CRAYON HOLDER.

1,355,627.

Specification of Letters Patent. Patented Oct. 12, 1920.

Application filed December 29, 1919. Serial No. 347,944.

To all whom it may concern:

Be it known that I, ANGELO M. TOZZI, a subject of the King of Italy, and resident of Bayonne, in the county of Hudson and State of New Jersey, have invented certain new and useful Improvements in Lead or Crayon Holders, of which the following is a specification.

This invention relates to that class of lead or crayon holders wherein the lead or crayon is protruded by manually operated step-by-step feeding devices.

The object of my invention is to provide a holder having feeding devices of simple and efficient construction and operation which not only permit the easy and positive projection of the lead or crayon to the proper extent and its retention in projected position, but also the ready retraction of the lead or crayon within the holder when desired.

According to my invention the holder comprises a tubular casing or handle provided within one end thereof with a frictional retaining device for a lead or crayon; a plunger is arranged within the casing and operable to bear against the inner end of the lead or crayon and advance the latter a limited extent to project its point beyond the end of the casing; a manually operative step-by-step feed-bar is arranged within and longitudinally of the casing and in operative relation to the plunger, and a unitary locking element is loosely contained within the casing and is adapted to be automatically positioned by gravity to couple the feed-bar and the plunger when the casing is held in position for writing, whereby when pressure is applied to said bar to move it toward the lead or crayon the plunger is correspondingly impelled in a manner to project the point of such lead or crayon beyond the casing. When the holder is inverted, the locking element is automatically disengaged from the feed-bar and plunger, thus permitting the lead to be readily pushed back into the casing.

Preferable forms of embodiment of my invention will be hereinafter described, and the scope of the invention then be defined in the appended claims.

In the drawings—

Figure 1 is a longitudinal vertical sec-

tion, enlarged, of a lead or crayon holder embodying my invention.

Figs. 2 and 3 are transverse sections of the same, on the lines 2—2 and 3—3 respectively of Fig. 1.

Fig. 4 is a longitudinal vertical section of a modified construction.

Figs. 5 and 6 are transverse sections, on the lines 5—5 and 6—6 of Fig. 4.

Fig. 7 is a side elevation of the loose lead or crayon container, showing a portion of the feed-bar associated therewith.

Fig. 8 is a side elevation of the piston and plunger device, showing a portion of the feed-bar and the locking element as in engaging position. Fig. 9 is a transverse section on the line 9—9 of Fig. 4.

Referring to the drawings, 10 designates a tubular casing or handle having a tapered end portion 11. Arranged within the tapered portion, centrally thereof, is a split guide tube 12 having an expanded top portion 13 which is snugly fitted and held within the casing. This tube is adapted to hold by friction the lead or crayon 14. Slidably mounted in the casing is a piston comprising a head 15 and a depending U-frame 16 carrying a central plunger 17 which is movable within and longitudinally of the guide tube 12 so as to bear against the upper end of the lead or crayon contained in the latter. The top of the piston 15 is angularly or conically recessed, as at 18. It is also provided with a vertical slot 19 through which loosely depends a flat feed-bar 20 which extends centrally and longitudinally of the casing. This bar is maintained normally in raised position by the action of a spring 21 which, being seated in a suitably-disposed cup or socket 22 fast within the casing, bears against a cross-pin 23 extending through the bar. The upper end of the bar presses against a cap 24 which is slidably fitted in the upper end of the casing and is suitably shaped to provide a convenient means for the application of vertical pressure to the bar. The cap is so constructed and mounted on the casing as to have capacity for a definite limited movement approximately equal in extent to the desired protrusion of the lead or crayon from the holder. In the present instance the tubular body of the cap is provided with a teat 25 which is

slidingly fitted in an annular recess 26 in the upper end of the casing, said body being longitudinally slotted, as at 27, to render it sufficiently contractible and expansible to 5 permit the body to be easily applied to the upper end of the casing and the teat 25 operatively engaged with the annular recess.

The lower portion of the bar 20 is provided longitudinally thereof with a succession of closely arranged transverse orifices 28 each of which is so proportioned as snugly to receive a unitary locking element, preferably a metal ball or pellet 29 which is loosely confined within the casing. The distance between the centers of two adjacent orifices is equal to the extent of the longitudinal movement of the cap, or substantially so. The ball 29 is so positioned within the casing that when the holder is in 20 substantially vertical position for writing, that is, point downward, the ball enters the recess 18 in the top of the piston and tends to roll by gravity toward the center of the recess in a manner to enter the opposing 25 orifice of the feed-bar. When the ball thus enters the orifice it effectually couples the bar to the piston head, and hence when the bar is slightly depressed against the action of the spring 21, by pressure applied to the 30 head 24, the piston and its plunger are correspondingly depressed, which plunger in its movement thus advances the lead or crayon and projects its point beyond the reduced end of the casing to the desired extent. This being done, the cap is released 35 from pressure, whereupon the feed-bar with the ball is raised by the action of the spring 21; the ball falling into the recess 18 of the piston and entering the next succeeding 40 lower orifice of the bar 20 presented thereto, thus again locking the bar and the piston and perfec-

45 By applying pressure to and releasing it from the cap, in alternate succession, the piston and therewith the plunger are advanced step-by-step and the lead thus correspondingly moved and its point uniformly projected to the desired extent from the 50 holder.

In order to retract the lead or crayon into the holder, it is merely necessary to invert the holder, in which case the ball gravitates from its engaging relation with an orifice 55 of the bar. Thereupon slight inward pressure being applied to the protruding end of the lead or crayon the latter will be pushed into the stationary guide tube 12 in a manner to press the plunger and its 60 piston backward. To project the lead or crayon from time to time the holder is held and its cap manipulated as previously described.

65 30 designates a tubular lead or crayon container which is fixedly supported within

the upper part of the casing, the base of said container being preferably swaged in the cup or socket 22. The bottom of the container is slotted, as at 31, for the free passage of the feed-bar.

70

In the form of my invention illustrated in Figs. 4 to 8, inclusive, the feed-bar, 20', is constituted by a unitary ratchet frame comprising two spaced parallel bars *a* connected intermediate of their ends by a cross-bar *b* and at their lower extremities by a basal part *c* which is fixed to, so as to be an integral part of such extremities after the piston 15' has been applied to the bars *a*. Formed in the inner edges of the lower portions of the bars are corresponding ratchet teeth 28'. The piston 15' carrying the plunger 17 is provided with diametrically opposite lateral notches *d* through which the bars *a* freely extend; and the top of the piston is formed with two oppositely inclined recesses 18' extending from the central ridge of the piston down to the respective bars. A spring 21 seated in the expanded top 13 of the guide-tube 12 and bearing against the basal part *c* of the bars maintains the ratchet frame normally raised.

75

The upper portions of the bars *a* are slidingly fitted in lateral guide ways *e* in the fixed lead or crayon container 30 and contact at their extremities with laterally projecting lips *f* formed on a depending tube *g* which is affixed to the interior of the top of the cap 24. Thus when pressure is applied to the cap the ratchet frame is depressed against the action of the spring.

80

When the holder is in position for writing the ball 29 is supported in one or the other of the recesses 18' of the piston and is engaged with the opposing tooth of the adjacent ratchet bar. Hence when the cap and the ratchet frame are slightly depressed by the action of the writer's finger on the cap as above mentioned, the ratchet tooth which bears upon the opposing ball, correspondingly depresses the piston and the plunger, and thus accordingly projects the point of the lead or crayon from the holder, similarly to the first described construction. Likewise when the holder is inverted the ball recedes from the engaged tooth of the adjacent ratchet bar and permits the lead or crayon to be pushed back into the guide-tube in the holder.

85

100 It is to be understood that I do not limit my invention to the specific details of construction herein disclosed, as the same may be modified within the principle of the invention and the scope of the appended claims.

90

110 I claim—

120 1. In a lead or crayon holder, the combination with a casing having at one end thereof means for frictionally holding a lead or crayon, of a plunger reciprocable 125

95

130

within and longitudinally of said casing and operative to advance the lead or crayon, a piston for said plunger having a recessed portion, a feed-bar reciprocable within and longitudinally of said casing and having a succession of spaced-apart locking portions, and a gravity locking element freely contained in said casing and adapted to enter the recess of the piston and bodily move into or out of engaging relation with a proximate locking portion of the feed-bar according to the position of the holder.

2. In a lead or crayon holder, the combination with a casing having a relatively fixed lead or crayon holding tube therein adjacent one end of the casing, of a plunger reciprocable within and longitudinally of said casing and tube, a piston for said plunger having a recessed portion, a feed-bar reciprocable within and longitudinally of said casing and having a succession of spaced-apart locking portions, means for operating said bar, and a gravity locking element loosely contained in said casing and adapted to enter the recess of the piston and bodily move into or out of engaging relation with a proximate locking portion of the feed-bar according to the position of the holder.

3. In a lead or crayon holder, the combination with a casing having at one end thereof means for frictionally holding a lead or crayon, of a plunger reciprocable within and longitudinally of said casing and operative to advance the lead or crayon, a piston for said plunger having a recessed portion, a feed-bar reciprocable within and longitudinally of said casing and having a succession of spaced-apart locking portions, and a pellet loosely contained in said casing and adapted to enter the recess of the piston and bodily move into or out of engaging relation with a proximate locking portion of the feed-bar according to the position of the holder.

4. In a lead or crayon holder, the combination with a casing having at one end thereof means for frictionally holding a lead or crayon, of a plunger reciprocable within and longitudinally of said casing and operative to advance the lead or crayon, a recessed centrally-perforated piston for said plunger, a feed-bar reciprocable within and longitudinally of said casing and having a succession of spaced-apart orifices, and a gravity locking ball freely contained in said casing and adapted to enter the recess of the piston and bodily move into or out of en-

gaging relation with a proximate orifice of the feed-bar according to the position of the holder.

5. In a lead or crayon holder, the combination with a casing having at its lower end means for frictionally holding a lead or crayon, of a plunger reciprocable within and longitudinally of said casing and operative to advance the lead or crayon, a piston mounted within the casing and controlling the plunger, said piston having a recessed upper portion, a feed-bar reciprocable within and longitudinally of said casing and having a succession of spaced-apart locking portions, a spring mounted within said casing so as to maintain the bar normally in raised position, a slideable pressure cap fitted to the upper end of the casing and co-acting with the feed-bar, and a pellet freely contained in the casing and adapted to enter the said recessed portion of the piston and bodily move into or out of engaging relation with a proximate locking portion of the feed-bar according to the position of the holder.

6. In a lead or crayon holder, the combination with a casing having at one end thereof means for frictionally holding a lead or crayon, of an ejector element reciprocable within and longitudinally of said casing and operative to advance the lead or crayon, a feed-bar reciprocable within and longitudinally of said casing and having a succession of spaced-apart locking portions, and a gravity locking ball freely contained in said casing, said element having a portion constructed and arranged to guide the ball into or out of engaging relation with a proximate locking portion of the feed-bar according to the position of the holder.

7. In a lead or crayon holder, the combination with a casing having at one end thereof means for frictionally holding a lead or crayon, of an ejector element reciprocable within and longitudinally of said casing and operative to advance the lead or crayon, a feed-bar reciprocable within and longitudinally of said casing and having a succession of spaced-apart locking portions, and a gravity ball for temporarily locking said element to the feed-bar, said element having an inclined ball supporting and guiding portion leading to the path of the locking portion of the feed-bar.

Signed at New York, in the county and State of New York, this 23d day of December, A. D. 1919.

ANGELO M. TOZZI.
